HOWARD M. COX, OF CHICAGO, ILLINOIS, ASSIGNOR TO JUDD LAUNDRY MACHINE COMPANY, OF WILMINGTON, DELAWARE, A CORPORATION OF DELAWARE.

ACTUATING MECHANISM.

1,112,983.

Specification of Letters Patent.

Patented Oct. 6, 1914.

Application filed November 22, 1912. Serial No. 732,961.

To all whom it may concern:

Be it known that I, HOWARD M. Cox, a citizen of the United States, residing at Chicago, in the county of Cook and State 5 of Illinois, have invented a certain new and useful Improvement in Actuating Mechanisms, of which the following is a specification.

My invention relates to actuating mechanisms for operating oscillating bodies.

The object of the invention is to provide simple and effective means for oscillating the body about its pivot, and as the invention is well adapted for washing machines, 15 I have illustrated it as embodied in a machine of that character.

I accomplish my object by the mechanism illustrated in the accompanying drawings, in which—

20 Figure 1 is a general side elevation of the machine. Fig. 2 is a plan view of the portion nearest the observer looking at side shown in Fig. 1. Fig. 3 is an enlarged view showing some of the details exhibited in Fig. 25 1. Fig. 4 is a sectional view taken on the line 4—4 of Fig. 3, and Fig. 5 is a perspective view of the reciprocating block or cross-head which is connected to the actuating spring.

30 Similar numerals refer to similar parts throughout the several views.

In the form of machine selected to illustrate the invention, there is a stationary frame comprising horizontal side beams 1 and cross beams 2 supported upon legs 3 rigidified by braces 4. The tub 5 which constitutes the body to be oscillated is pivoted to rock back and forth upon pivots 6 supported upon the frame. In the form 40 shown, these are trunnions held at one end in castings 7, secured to the sides of the tub and supported at the other ends in castings 8, which rest upon the horizontal side beams 1.

45 Articulately connected to the tub, preferably near the upper edge thereof, is an actuating spring 10 which carries a casting 11 at its lower end. A pin 12 extends outwardly from said casting, and is held in position in any suitable manner, for example, by making a drive fit. A connecting rod 13 is articulately connected to said pin and is actuated by a crank 14 extending from a shaft 15, supported upon a bracket 16

55 mounted on the frame as best shown in Figs. 1 and 2. Said pin is guided in its movement by a guide consisting, according to the present design, of a base 20, and a cap 21. The base is preferably formed integral with the casting 8; and the cap is bolted or 60 otherwise rigidly held in position. The guide surfaces of said guide are curved in the present instance, although the radius of curvature may be varied as desired, even to infinity in which case the guide surfaces 65 would be straight.

Sliding within the guide 20—21 is a block 24 shown in perspective in Fig. 5. Said block, which practically constitutes a cross-head, is here shown to be provided with 70 flanges 25 holding it securely in position within the guide. Said block is apertured to receive pin 12, and the parts are held together with the assistance of the nut 26 screwing on the outer threaded end of the 75 pin 12. Auxiliary springs 30 and 31 are connected at their lower end to the frame legs 3 and at the upper end to the tub 5. In the preferred design the point of attachment at the upper end of the springs is upon 80 extensions 32 formed integral with the casting 7.

In operation, when shaft 15 is rotated and the rod 13 caused to move back and forth it causes block 24 to slide back and forth in 85 the guide 20—21. When the block moves toward the right from the central position shown in Fig. 1, the actuating spring 10 tends to rock the tub toward the rod and thus stretch the spring 31. The momentum 90 of the tub causes it to overthrow, and consequently block 24 commences its return travel before the tub does. The returning block first partially releases and then re-stretches the spring 10 and finally this 95 spring and the springs 31 causes the tub to oscillate in the return direction. This movement is repeated at the opposite end of the throw and continues as long as the machine is in operation, the tub oscillating 100 back and forth and stretching, first, the springs 31 and then the spring 30.

It will be understood that I do not wish to be limited to the precise form of a sliding element here shown nor to the precise form 105 of guide in which the oscillating body operates, the essentials of my invention being pointed out in the accompanying claims.

Having thus described my invention, what I claim as new, and desire to secure by Letters Patent, is:

1. In combination, an oscillating body, a reciprocating sliding element, a spring connected at one end to said oscillating body and at the other end to said sliding element, and means for causing said element to reciprocate.
- 10 2. In combination, a stationary frame, a body pivotally supported thereon, an element slidably mounted on said frame, a spring connected to said pivoted body and to said sliding element and means for causing said element to slide back and forth.
- 15 3. In combination, a stationary frame, a guide mounted thereon, a block slidable upon said guide, means for reciprocating said block, a body pivotally supported on said frame, and a spring connected at one end to said block and at the other end to said body.
- 20 4. In combination, a pivoted body, a reciprocating sliding block, a spring connected at one end to said block and at the other end to said body, a rotating eccentric, an eccentric rod connected to said eccentric and adapted to actuate said block backward and forward.
- 25 5. In combination, a pivoted body, an

actuating spring connected thereto for oscillating said body about the pivot, means for actuating said spring, a sliding element for controlling the path of movement of the free end of said spring, and means for 35 guiding said sliding element.

6. In combination, a pivoted body, an actuating spring connected thereto for oscillating said body about its pivot, a rod connected to said spring for actuating it, a 40 stationary guide, and an element sliding back and forth in said guide and connected to said rod for controlling the movement thereof, said sliding element being actuated by said rod.

45 7. In combination, a pivoted body, an actuating spring connected thereto, auxiliary springs also connected to said body for assisting in causing the oscillation thereof, a block connected to said actuating spring, a guide for said block, and eccentric mechanism for causing said block to reciprocate in its guide.

In witness whereof, I have hereunto subscribed my name in the presence of two witnesses.

HOWARD M. COX.
